Ira Powers

UNITED STATES PATENT OFFICE.

IRA POWARS, OF WAUKEGAN, ILLINOIS.

IMPROVEMENT IN DOOR-SPRING.

Specification forming part of Letters Patent No. **86,318**, dated January 26, 1869.

To all whom it may concern:

Be it known that I, IRA POWARS, a citizen of Waukegan, in the State of Illinois, have invented a new and Improved Graduated Spring for Doors, Gates, &c.; and I do hereby declare that the following is a full and exact description thereof, reference being had to the accompanying drawings, and to the letters of reference marked thereon.

The nature of my invention consists in providing a door or gate with a graduated spring, upon which is always an equal pressure, whether the door be open or shut, thus avoiding the wear and strain to which door-springs are usually subjected.

To enable others skilled in the art to make and use my invention, I will proceed to describe its construction and operation.

Figure 1 is a perspective view with the door partly open. Fig. 2 is a sectional view on the line *x x*.

The spring A is fastened to the door or gate by screws or their equivalents at *a b*, and the opposite end, *e*, of the spring A, which may be supplied with a roller attached thereto, passes over and around the block C, on which it freely moves, in the groove *i*. The block C is secured

to the post or facing by screws or their equivalents.

The spring A can be made of steel, brass, or any other suitable material, and will be found to be more economical than the springs now in use, as it lasts longer, owing to the equal pressure upon it at all times, and no danger to be apprehended from overstraining.

When it is required to increase or lessen the pressure of the spring A, it is only necessary to turn the screw *b*.

I am aware that gates have been made with springs and spring-hinges, and I distinctly disclaim everything which is shown in the forfeited application of Christopher Fraelish, filed June 10, 1865.

What I claim as my invention, and desire to secure by Letters Patent, is—

The spring A, in combination with the block C, the plate *c*, and the screws *a b*, all constructed and operating substantially as shown, and for the purpose set forth.

IRA POWARS.
